Weder & Hering, an County
ATTORNEYS.

UNITED STATES PATENT OFFICE

HARRY B. GRINER, OF OAKLYN, NEW JERSEY

FASTENER FOR AWNINGS

Application filed May 3, 1928. Serial No. 274,778.

My invention relates to a new and useful fastener for securing awnings, curtains and the like.

It has been the practice heretofore to employ a screw or screw eye adapted to pass through eyelets or grommets in the upper hem of the awning and to be driven into the frame work of a window or porch, said eye, screw or the like to be unscrewed from the wooden frame work when it was desired to take the awning down. In addition to consuming considerable time and effort in screwing and unscrewing the large number of fastening devices employed in putting up or taking down the awnings, this practice further resulted in considerable damage to the wooden frame work on which the awnings are supported, since, as is well known, a screw or the like is liable to cease to hold after it has been driven once or twice at the same point or into the same hole, thus rendering it necessary to plug the old holes made by previous driving of the screw, or the driving of the screw into the wooden frame work at a different point, with obvious disadvantages. Furthermore, under this practice it was necessary to collect and carefully preserve the large number of screws or screw eyes employed from season to season, or else a fresh supply had to be purchased, all of which was both expensive and inconvenient.

It is the object of my invention to provide a fastener for securing awnings, curtains and the like which overcomes all of the above disadvantages and whereby awnings can be fastened or detached from the frame work supporting the same at a minimum cost, in a minimum time and with minimum effort.

Other objects of my invention will be more apparent from the following description and the annexed drawings.

To the above ends my invention consists of a single, integral angular fastening device comprising a body portion and two resilient prongs or arms, the latter being adapted to be snapped on to and to engage the stem of a permanently inserted screw or screw eye, over the hem of an awning to hold the latter in place upon said stem.

My invention further consists of various

other novel features of construction and advantage, hereinafter described and claimed.

For the purpose of illustrating my invention I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of the instrumentalities as herein shown and described.

In the accompanying drawings.

Figure 1, represents a perspective view showing my novel awning fastener in use, and a portion of an awning to which the same is applicable.

Figure 2, represents on an enlarged scale a perspective view of my novel fastener detached.

Figure 3, represents a front elevation of Figure 2.

Figure 4, represents on an enlarged scale a section on line 4-4, Figure 1.

Figure 5, represents a perspective view of a modified form of fastener embodying my invention.

Referring to the drawings, in which like reference characters indicate like parts, 1 designates a fastener embodying my invention, comprising a sheet metal body portion 2, which is preferably round or of other contour, and is provided with the integral arms 3 and 4, which are preferably deflected upwardly at a right angle to said body portion. The spring arms or limbs may have their ends rounded as at 5 so as to form the throat 6 which merges at its lower end into the enlarged opening 7, which merges into the slot 9, a portion of which is between the lower portion of the vertical limbs 3 and 4, from which said slot extends into the eye 8 in the body 2.

By the above construction, a light and efficient fastener is produced, which can be manually grasped and manipulated by the body 2 as a handle and as the walls of the throat 6 are rounded above and below its narrowest

portion, the device is readily applied and removed.

In using my novel fastener, the screws 10 are driven permanently into the wooden frame or jamb 11 to which it is desired to secure the awning, and the metallic eyelet or grommet 12, usually provided on the hem 13 of the awning 28 is passed over the head 14 of the screw. The fastener 1 is then grasped 10 or manipulated by the body portion 2, and the upper rounded edges of the throat 6 of the resilient limbs 3 and 4 are pressed upwardly against the screw whereupon said limbs separate slightly and the fastener slides into the 15 position seen in Figures 1 and 4 and the shank of the screw becomes seated in the rounded opening 7, which is too small to permit the heads 14 of said screws to pass therethrough, thus maintaining the awning in position. 20 When it is desired to remove the awning, it is merely necessary to pull the fastener 1 downwardly or in the reverse direction, to permit the shank or stem of the screws 10 to be disengaged from the rounded opening 7 25 and to pass by the throat 6 whereupon the eyelet 12 on the hem 13 of the awning 14 is slipped over or pulled outwardly from the head 14 of the screw 10.

The openings 8 and 9 in the body portion 30 of my novel fastener provide lightness of structure and afford added resiliency to the limbs 3 and 4, as will be apparent. The foregoing structure may be easily and cheaply stamped or pressed out of sheet metal.

35 In Figure 5, I have shown a modified form of my invention, wherein I illustrate the use of wire for making my novel fastener, in lieu of sheet metal or the like. In this construction, which is very light and inexpensive to 40 make, the body portion is formed of the integral wire frame composed of the members 15, 16 and 17 which in conjunction with the inwardly deflected portions 18 form a substantially rectangular frame or body serving 45 as a handle whereby the device may be manipulated. The portions 18 form a narrow slot 19 and then are deflected outwardly to form the limbs 20 and 21 which form the rounded opening or seat 22 for the reception 50 of the stem 10 of the fastening screw, the upper terminals of said arms 20 and 21 being deflected inwardly towards each other to form the throat 23 corresponding to the throat 6 through which the stem 10 of the 55 fastening screw is adapted to be passed in the manner above described. The extreme ends of the arms 20 and 21 are bent or otherwise disposed to form the eyes 25, which present rounded edges or surfaces to facilitate the 60 manipulation of the device, as already explained.

This construction possesses extreme lightness and resiliency and is inexpensive to manufacture.

65 By my invention I thus eliminate the ne-

cessity of unscrewing or removing the fastening screws from the frame or jamb 11, when the awning is taken down and replacing them when the awning is again put up, thereby eliminating a great deal of labor heretofore necessary and eliminating all damage to the wood work which would necessarily result by repeated driving of screws or the like thereinto.

Furthermore, when an awning has been 75 removed, the fastening devices of my novel invention can be instantly snapped back into position on the fastening screws to remain there ready for use in the succeeding season.

It will thus be apparent that I have devised a novel awning fastener, which is highly efficient in use, and which effects great economy in time, labor and material, since the same can be manufactured by a single stamping or punching operation, and since it 85 can be applied or removed by single movement in one direction.

While I have described my novel fastener as applied to securing an awning in place, it is to be understood that the same is equally 90 applicable with slight or no variation, to the fastening of curtains, and the like, and wherever it is desired to secure an object temporarily and detachably to a permanent support, along the general lines hereinabove set 95 forth.

I am aware that the invention may be embodied in other specific forms without departing from the spirit or essential attributes thereof, and I therefore desire the present 10 embodiment to be considered in all respects as illustrative and not restrictive, reference being had to the appended claims rather than to the foregoing description to indicate the scope of the invention.

Having thus described my invention what I claim as new and desire to secure by Letters Patent, is:—

1. In a device of the character stated, an elongated rigid frame-work, a fastening member extended laterally from said frame-work, a sheet having an eyelet therein engaging said member, a horizontal body portion having an eye therein, and a pair of resilient limbs vertically extended therefrom, there being a throat formed between the inner edges of said vertically extended limbs for engaging said fastening member, which limbs parallel said frame-work and abut against said sheet, said throat merging into an upper wider opening positioned intermediate the central portions of said limbs to provide lightness of structure and resiliency of said limbs, said throat communicating with said eye in said horizontal body portion through a slot formed partly in said limbs and partly in said body, the latter serving as a handle and extending at substantially a right angle to said limbs.

2. As a new article of manufacture, a one-

piece fastener comprising a flat body portion and a pair of flat arms integral with and at an angle to said body portion, there being an enlarged opening in said body portion, a second enlarged opening formed in the central portion of said arms and a narrow slot at the junction of said arms with said body interconnecting said enlarged openings and the free ends of said arms being diverged to form a tapering throat portion leading to said second enlarged opening.
